UNITED STATES PATENT OFFICE.

GEORGE ROSS, OF NEWPORT, KENTUCKY.

IMPROVEMENT IN PATTERNS FOR MOLDING PIPES.

Specification forming part of Letters Patent No. 37,981, dated March 24, 1863.

To all whom it may concern:

Be it known that I, GEORGE Ross, of Newport, in the county of Campbell and State of Kentucky, have invented a new and useful Improvement in Patterns for Molding Pipes, &c.; and I do hereby declare that the following is a full, clear, and exact description of the same, reference being had to the accompanying drawings, forming a part of this specification, in which—

Figure 1 represents a vertical central section of my invention. Fig. 2 is a horizontal section of the same, taken in the plane indicated by the line xx , Fig. 1.

Similar letters of reference in both views indicate corresponding parts.

The object of this invention is to strengthen cast-iron pipes at such places where the same have to be tapped for small or branch pipes.

The invention consists in the application to the pattern which is used in molding pipes of a sectional ring or belt, or of a series of movable buttons arranged in such a manner that the same can be pushed out beyond the surface of the pattern, and drawn back again while the pattern is in the sand, thus producing a belt or projections which strengthen the pipe and increase the thickness of the metal at such places where the pipe is to be tapped.

The invention consists, also, in the arrangement of a rising and falling conical plunger acting upon the ends of studs which are inserted into the several sections of the ring or belt on the pattern, in combination with springs, in such a manner that on depressing said plunger the sectional belt is forced out beyond the surface of the pattern, and on raising the plunger said sections are drawn back automatically by the action of the springs.

To enable others skilled in the art to make and use my invention, I will proceed to describe it with reference to the drawings.

A represents a pattern made of cast-iron or other suitable material, and used in molding pipes. Such patterns are generally from ten to twelve feet long, and they, together with the flasks, are placed in a vertical position into a pit, and the sand is rammed round them, and after the pattern has been drawn a suitable core is inserted, and the mold is ready for casting. With ordinary patterns the bodies of the pipes become of a uniform thickness

from end to end, and if the pipe is to be tapped to receive a branch pipe the metal affords a very short hold to the thread, and the slightest accident causes said branch pipes to work loose. This difficulty I have obviated by applying to the pattern a ring or belt, B, made of brass or other suitable material, and placed into a recess, a , of such a depth that when the ring is in its outer surface is flush with the surface of the pattern. The ring B is made in four (more or less) sections, b , and the adjoining sections overlap each other by means of projecting lips c , as clearly shown in Fig. 2, so that said sections can be expanded without opening a gap between their ends. Each of the sections b is provided with a stud, d , which extends into the interior of the pattern.

C are springs, the ends of which are forked and catch into annular necks in the inner ends of the studs d , and which have a tendency to force the studs, and with them the sections of the ring B, toward the center of the pattern.

D is a conical plunger which is firmly secured to a rod, E. This rod is guided below by a plate, F, secured in the pattern below the ring, and above by a plate, G, fastened to the top edge of the pattern. A nut, e , prevents said rod from coming out. The rod E is provided with a handle, f , whereby the plunger is raised or depressed. On depressing the plunger it acts upon the inner ends of the studs d , and the sections of the rings B are forced out beyond the surface of the pattern. On raising the plunger the sections b of the ring recede simultaneously by the action of the springs C. The handle f of the rod E extends beyond the upper end of the pattern, and after the sand has been rammed round the pattern said handle is depressed, and the ring B leaves a circular impression in the sand. On raising the handle the ring recedes and the pattern can now be withdrawn in the ordinary manner.

It is obvious that instead of the movable ring B single sections or buttons might be employed at certain intervals to strengthen the metal at such places where the pipes are to be tapped; but the belts produced by the movable rings are more convenient, because they permit of tapping the pipe on any side.

What I claim as new, and desire to secure by Letters Patent, is—

1. The application to the pattern A of a

movable sectional ring, B, or its equivalent, capable of being pushed out and drawn in while the pattern is in the sand, in the manner and for the purpose substantially as specified.

2. The arrangement of the rising and falling conical plunger D and springs C, in combination with the studs d and sectional ring

B, constructed and operating substantially as and for the purpose shown and described.

GEORGE ROSS.
